UNITED STATES PATENT OFFICE.

CHARLES M. FEE, OF FULTON, MISSOURI.

ATTACHMENT FOR PUG MILLS.

1,419,833.

Specification of Letters Patent. Patented June 13, 1922.

Application filed July 1, 1919. Serial No. 307,902.

To all whom it may concern:

Be it known that I, CHARLES M. FEE, a citizen of the United States, residing at Fulton, in the county of Callaway and State 5 of Missouri, have invented new and useful Improvements in Attachments for Pug Mills, of which the following is a specification.

This invention relates to an attachment 10 for pug mills and has for its primary object to provide an attachment for determining the condition of the column of mud issuing from the mill by giving signals according to whether the mud is hard or soft.

15 Another object of the invention is to provide means for reducing the expense for running a pug mill.

An object of the invention is to provide a simple device for giving immediate information when the degree of hardness of the 20 mud changes.

With these and other objects in view the invention will be better understood from the following detailed description taken in connection with the accompanying drawings, 25 wherein:—

Figure 1 is a fragmentary side elevation of a pug mill showing my invention attached thereto.

30 Figure 2 is a front elevation of the device. Figure 3 is a top plan view.

Again referring to the drawings showing one of the many forms in which the invention may be constructed the numeral 1 designates a bracket of U-shape formation secured to the pug mill B at the point where the mud issues from the mill. Fitted to the bracket so as to swing in an arc of a circle is an L-shaped member 2 one limb 3 40 of which being so disposed that it will constantly press upon the column of mud C issuing from the mill.

For the purpose of regulating the pressure of the limb 3 upon the column of mud 45 so that the same may sink into the mud when the latter is soft or to be elevated when the mud is hard I provide the regulator 4 consisting of a bolt 5 loosely passing through the bracket and the member 2 and encircled by a coil spring 6 one end of which presses against the member 2 while the other end is engaged by the plate 7 slidable on the bolt so as to vary the expansive action of the spring 6. This plate 7 is adjustable and 55 acted upon by adjusting screws 8 threaded

into the bracket. The numeral 9 designates the switch one element of which is in the form of a contact strip 10 secured to the member 2 so as to move therewith. The other element of this switch is in the form 60 of adjustable contacts 11 and 12 arranged in the path of movement of the contact strip 10 so that when the member 2 reaches a predetermined position the strip 10 will engage the contacts for closing the signal circuits 65 now to be described. Connected to the contact 11 is a conductor 13 in which is arranged a signal device shown in the drawings as a bulb 14 which may be of any color. When the bulb 14 is illuminated it indicates 70 that the mud is soft. Connected to the contact 12 is a conductor 15 in which is arranged a signal bulb 16 of a different color from the bulb 14 for indicating when the mud is hard. A common return conductor 17 connects to the first two mentioned conductors and to the contact strip and has arranged 75 therein a battery 18.

From the foregoing description taken in connection with the accompanying drawing 80 it will be apparent that when the degree of hardness of the column of mud C lowers a predetermined amount according to the setting of the device the arm L will be forced into the column of mud by the expanding 85 action of the spring 6 which brings the strip 10 into engagement with the contact 11 thereby closing the circuit in which the bulb 14 is arranged. This will immediately give the signal to the operator of the pug mill so 90 that he can act accordingly. Should the reverse take place, that is to say the degree of hardness of the column of mud increases a predetermined amount the arm 2 will swing about its pivot to bring the contact 10 into 95 engagement with the contact 12 thus closing the circuit of bulb 16 and thereby give a visual indication to the operator of the pug mill that the column of mud is too hard. Thus it will be seen that in a very simple 100 inexpensive manner I am able to give visual indications when the degree of hardness of the mud reduces below a predetermined degree thereby dispensing with a table man in the 105 operation of pug mills and further assuring the proper degree of hardness for obtaining the best results when making bricks or tiles.

It is of course to be understood that the 110

invention may be constructed in various other manners and the parts associated in other relations and therefore I do not desire to be limited in any manner except as set forth in the claims hereunto appended.

What I claim is:—

1. An attachment for pug mills comprising a signal device including a bracket secured upon the outlet end of the pug mill, 10 a pair of spaced contacts carried by said bracket, a pair of signal members connected with said contacts and connected with a source of current, a spring pressed arm pivoted upon the outlet end of the pug mill and 15 including one portion engageable with the column of mud issuing from the pug mill and including another portion extending at a right angle, and a contact member carried by said mentioned portion of the arm and 20 engageable with one or the other of said first named contacts whereby to close the circuit through one signal or the other.
2. A signal attachment for pug mills comprising a bracket member secured upon the 25 discharge member of the pug mill, a pair of spaced contacts carried by said bracket, a pair of signal members connected with said contacts and connected with a source of current, an L-shaped arm pivoted upon the 30 outlet end of the pug mill and including one portion engaging the column of mud issuing from the pug mill and including another portion at an angle thereto, an adjustable spring tensioned upon the second portion

of said arm whereby to vary the degree of pressure upon the column of mud, and a contact carried by the second mentioned portion of the arm and adapted to engage one or the other of said first named contacts whereby to energize one or the other of said 40 signals.

3. A signal device for pug mills comprising an L-shaped bracket secured upon the outlet end of a pug mill, a pair of spaced contacts carried by said bracket, a pair of 45 signal members connected with said contacts and connected with a source of current, an L-shaped lever pivoted upon the outlet end of the pug mill and including one arm engaging the column of mud issuing therefrom and 50 further including a second arm extending at an angle, a contact carried by said second named arm and connected with the source of current, said last named contact being engageable with one or the other of said first 55 named contacts, an adjustable spring tension associated with said bracket and engaging said second named arm whereby to vary the pressure of the first named arm against the column of mud.

4. An indicating means comprising a pug mill and means for indicating a change from normal in the density of the material forced from the mill.

In testimony whereof I affix my signature.

CHARLES M. FEE.
